COMBINED TELEVISION, RADIO, AND PHONOGRAPH CABINET OR SIMILAR ARTICLE

Jack Barofsky, Los Angeles, Calif.

Application April 21, 1948, Serial No. 145,886

Term of patent 14 years

(Cl. D56—4)

To all whom it may concern:

Be it known that I, Jack Barofsky, a citizen of the United States, residing at Los Angeles, in the county of Los Angeles and State of California, have invented a new, original, and ornamental Design for a Combined Television, Radio, and Phonograph Cabinet or Similar Article, of which the following is a specification, reference being had to the accompanying drawings, forming part thereof.

Figure 1 is a front perspective view of a combined television, radio, and phonograph cabinet or similar article, showing my new design.

Figure 2 is a side elevational view thereof.

Figure 3 is a front elevational view thereof.

Figure 4 is a top plan view thereof.

The side opposite that shown in the drawings is the same as the side illustrated. The back is plain.

The dominant features of my design are shown in solid lines in the drawings.

I claim:

The ornamental design for a combined television, radio, and phonograph cabinet or similar article, as shown and described.

JACK BAROFSKY.
